HARVEY B. REPETTO, OF WHEELING, WEST VIRGINIA, ASSIGNOR TO WHEELING STOVE & RANGE COMPANY, OF WHEELING, WEST VIRGINIA, A CORPORATION OF WEST VIRGINIA.

OIL-HEATING STOVE.

1,294,831.

Specification of Letters Patent. Patented Feb. 18, 1919.

Application filed May 6, 1918. Serial No. 232,722.

To all whom it may concern:

Be it known that I, HARVEY B. REPETTO, a citizen of the United States of America, and resident of Wheeling, county of Ohio, and State of West Virginia, have invented 5 certain new and useful Improvements in Oil-Heating Stoves, of which the following is a specification.

This invention relates specifically to oil 10 heaters, and it has for its primary object to provide an oil-burning heating stove which is particularly adapted for use in heating the rooms of buildings.

A further object is to provide a simple, 15 economical and comparatively inexpensive form of oil heater which requires but little and infrequent attention on the part of the user; which is so constructed that the heat-generating parts thereof may be conveniently removed from within the heater casing, as for cleansing, filling with oil, lighting and extinguishing, and which is particularly efficient as a heat generator.

In describing the invention in detail, reference is herein had to the accompanying 25 drawings, in which—

Figure 1 is a perspective view of the invention, and—

Fig. 2 is a partial vertical section of the 30 same.

Referring to said drawings; in which like designating characters distinguish like parts throughout the several views—

1 indicates a stove casing of a type which 35 is more or less common in gas stoves, the same being preferably composed of sheet metal and having a general rectangular form. Said casing has an open front, and disposed within said casing on the plane of 40 the lower end of the opening in its front is a horizontal shelf 2 which serves as a rest or support for a sheet-metal oil container or tank 3. Said tank is of shallow box-like form and carries upon its top in alined 45 relation a plurality of upright circular neck members 4 each of which encircles an opening 5 in said top. Said neck members are adapted to receive in seated relation thereto lamp burners 6 carrying wicks 7 which de- 50 pend into the tank 3 through the openings 5. Said lamp burners are designed to re- 55 movably support thereon glass lamp chimneys 8, as shown.

The tank 3 is slidably mounted upon the 55 shelf 2 and normally occupies a position in

which its front face is substantially flush with, or lies in the plane of, the front part of the casing. As shown in the drawings, lateral flanges 9 and a downwardly extending flange 10 is provided on the outer end 60 of the tank, such flanges being adapted to engage the front of the casing for limiting the extent of inward movement of the tank. Such flanges may be dispensed with, however, and a suitable stop-flange, as 11, provided upon the shelf 2 at the proper distance from its front end. 65

The tank may be moved outward, or withdrawn, to any extent desired in the manner of a drawer, a suitable pull-handle 12 being 70 mounted on the front wall, or face, thereof to facilitate such withdrawal and the return of the tank to its normal position.

Suitably mounted within the rear part of the casing is an inclined sheet-metal heat reflector 13 which may be of a common stepped form. Said reflector terminates at its lower end in approximately the plane of the top of the tank-receiving space so that it will closely overlie the tank, as shown in 80 Fig. 2.

The neck members 4 upon which the lamp burners 6 are carried are located forward of the center line of the tank so that the lower end of said reflector 13 may occupy a position midway or slightly in advance of the center transverse line of the casing, as shown.

In the normal position of the tank the lamp burners are located within the casing 90 with the tops of the chimneys 8 disposed below the top of the casing such a distance that draft through said chimneys is not unduly interfered with. When it is desired to light or extinguish the lamps, the tank is 95 withdrawn to the extent that the chimneys are disposed outside the front of the casing, in which position said chimneys may be removed and replaced without hindrance. Or, when a thorough cleansing of the heater is 100 to be performed, the tank may be wholly removed from the casing.

A suitable cap-covered filler opening 14 is provided in the tank at a readily accessible point. 105

What is claimed is—

1. An oil heating stove comprising a stove casing having an open front, an oil container of drawer-like form disposed within the lower part of said casing, a plurality of 110

- 2
- lamp burners carried by said container, chimneys carried by said burners with their upper ends in close proximity to the top of said casing, said container with its superposed burners and chimneys being bodily 5 slideable through said open front to and from an inclosed constantly-exposed position within said casing, and a heat reflector mounted within the rear part of said casing, said reflector being downwardly and forwardly inclined and terminating at its lower end in close proximity to the plane of the top of said container so that the latter is slideable thereunder, said lower end being also disposed adjacent to the position of the burners 10 when the container occupies its normal inclosed position, so that approximately all of said container located rearward of said burners is thereby concealed.
- 15 2. An oil heating stove comprising a stove casing having an open front, an oil container, a support for said container located in an elevated position within the lower part of said casing, said container being of drawer-like form and having horizontal drawer-like sliding movement on said support, a plurality of lamp burners carried by said container, glass chimneys carried by said burners, the upper ends of said chimneys being located in close proximity to the 20 top of the casing, and a heat reflector fixed within said casing and having its lower end disposed in a position wherein it overlies said container both when the latter is in its operative position and in an outwardly moved position in which the burners occupy withdrawn chimney-uncovered position and preventing tilting of said container when the latter occupies said outwardly moved position. 25
3. An oil heating stove comprising a shallow drawer-like oil container, a plurality of lamp burners carried by said container, chimneys carried by said burners, and a stove casing inclosing said parts, said casing having an open front through which said parts are bodily movable to and from inclosed position wherein the upper ends of said chimneys closely approach the top of the casing, and inclined heat reflecting means having its lower end normally overlying said container adjacent to and rearward of said burners. 30
- In testimony whereof, I affix my signature in presence of two subscribing witnesses. 35
